UNITED STATES PATENT OFFICE.

EDWIN J. HILLER, OF TAYLORVILLE, ILLINOIS.

GUTTER-HANGER.

1,076,367.

Specification of Letters Patent. Patented Oct. 21, 1913.

Application filed December 28, 1912. Serial No. 739,093.

To all whom it may concern:

Be it known that I, EDWIN J. HILLER, a citizen of the United States, residing at Taylorville, in the county of Christian and State of Illinois, have invented new and useful Improvements in Gutter-Hangers, of which the following is a specification.

This invention relates to gutter hangers.

An object of the invention is to provide a gutter hanger which will be simple in construction, durable in use and which will have combined therewith such structural features as to permit the hanger to be readily associated with and disconnected from a gutter and which will also be constructed whereby it may be readily attached to or removed from the roof of a building.

In the drawing forming a portion of this application, and in which like letters of reference indicate similar parts in the several views:—Figure 1 is a section through a gutter showing the application of the hanger thereto. Fig. 2 is a perspective view of the hanger.

The hanger comprises an embracing member 1 which is preferably constructed of flat sheet galvanized metal. This member comprises a curved bottom portion 2 which is adapted to be extended beneath the bottom and against the sides of the gutter A as shown in Fig. 1. The portion 2 is connected by the loop portion 3 to the top horizontal bar 4. The loop 3 is offset as at 5 from the bar 4 so that the latter when associated with the gutter is disposed below the plane of the upper edge of the gutter. The said bar 4 has its free end doubled on itself and formed to present a hook 6 in which is formed a rectangular opening 7. The loop 3 of the member 1 is adapted to receive the rolled front edge B of the gutter, while the straight rear edge of the gutter is adapted to be extended beneath the tongue 8 of the hook 6.

With a view to securely holding the member 1 properly associated with the gutter I form on the free end of the portion 2 a tongue 9 which is adapted to be extended through the slot 7 in the hook 6 and then

bent against the bar 4 as at 10. In this manner the free terminal of the portion 2 and the bar 4 are securely connected together. The bracket 11 is formed by folding the bar 4 on itself so as to provide an upper horizontally disposed branch 11^a whose inner end is extended into the tongue 9 and whose outer end is extended into a vertical portion 12. The portion 11^a of the bracket is provided with passages 15 which are arranged in staggered relation. The bar 4 and the branch 11^a thereof are stamped to provide substantially V-tongues A which are both struck up or upset against the upper side of the portion 11^a. If desired solder may be poured over the tongues after they are stamped up as shown in Fig. 3 so as to hold them in their connected positions.

The bracket 11 is adapted to be extended beneath the shingles of a roof and by arranging the passages 15 as shown, nails or like fastening devices may be driven through the shingles and through the passages 15 without liability of splitting the shingles. As stated the bar 4 is disposed below the plane of the upper edge of the gutter and in view thereof water dropping from the roof and following the bracket 11 will be taken up by the bar 4. The abruptness of the hook of the bar 4 and the offset 5 serve to prevent the water from flowing by capillary attraction over the sides of the vessel. As stated the water will be collected by the bar 4 where it will be free to drip directly into the gutter as is understood.

I claim:

A gutter hanger comprising a single piece of metal provided with a curved gutter embracing portion having a loop at one end receiving the bend of the gutter, the opposite free end of the curved portion having a bendable extension thereon, the metal from the loop of said curved portion being extended downwardly and then horizontally toward the opposite end of the gutter to form a connecting bar and then upwardly and terminally folded on itself and extended at the center of the bar and provided with an upwardly-extending attaching

bracket, the folded portions of the bar being
up-struck to provide a hanger having an
aperture therein for the reception of the
bendable end of said curved portion, and
5 spurs stamped from the body of the bar and
extending through the adjacent folded pos-
tion thereof and upstruck thereagainst.

In testimony whereof I affix my signature
in presence of two witnesses.

EDWIN J. HILLER.
